UNITED STATES PATENT OFFICE.

JOHN H. JULIAN, OF TROY, OHIO.

PERMUTATION-PADLOCK.

SPECIFICATION forming part of Letters Patent No. 353,031, dated November 23, 1886.

Application filed May 10, 1886. Serial No. 201,741. (Model.)

To all whom it may concern:

Be it known that I, JOHN H. JULIAN, a citizen of the United States, residing at Troy, in the county of Miami and State of Ohio, have 5 invented certain new and useful Improvements in Permutation-Padlocks, of which the following is a specification.

My invention relates to improvements in permutation - padlocks, and particularly relates to that class of padlocks in which a series of tumblers or locking-plates in a cylindrical casing are used in connection with a hasp, the legs of which are adapted to be engaged by said tumblers.

15 The objects of my invention are: first, to so construct and arrange the hasp in connection with the tumblers that the said tumblers will be locked when the hasp is withdrawn to open the lock, and thus guard against the accidental 20 turning of the said tumblers while the lock is open, which would necessitate going over the combination before the lock could again be closed; second, to so construct and arrange the hasp in connection with the tumblers that the 25 said hasp will be capable of a slight longitudinal movement in relation to the upper tumblers to permit the said hasp to enter the notch in the lower tumbler without engaging or coming in contact with the other tumblers 30 of the series, and thus hold the dial-plate until the hasp is inserted to its normal position, whereby the possibility of "feeling" the notches in the respective tumblers by drawing on the hasp as the dial-plate is revolved is 35 precluded; third, to so construct and arrange the lower tumblers in relation to the hasp that said hasp is adapted to engage with a series of false or blind notches by which the dial-plate will be held against revolution when 40 the hasp is drawn into said notches, whereby the possibilities of working the combination will be reduced.

My invention consists in the various constructions and combinations of parts herein- 45 after described, and pointed out in the claims.

In the accompanying drawings, Figure 1 is a 50 sectional elevation of a lock embodying my invention, the hasp being shown therein. Fig. 2 is a sectional elevation of the same partly in

and 4 are respectively a bottom plan view and a vertical sectional view of the outer casing, showing the manner of securing the hasp therein. Figs. 5 to 9 are detailed views of some of the parts, which will be referred to 55 hereinafter.

In the said drawings, A represents the outer case, at the lower end of which is journaled a dial-plate, A'.

B is the hasp, the legs a a' of which are 60 adapted to be inserted through openings b b' in the top of the casing A.

The dial-plate A' is held in position by and adapted to revolve on a stud, c, which extends centrally through the casing A, and is 65 secured at the top of said casing by a nut, c'. A central opening, c², is provided in the top of the case A, through which the end of the stud c is adapted to project to be engaged by the nut c'. This opening is preferably made 70 in the form of a square with one corner cut off, as shown in Fig. 3, the end of the stud being shouldered down and correspondingly shaped, as shown at c², to fit said opening. The stud c is thus held against revolution in 75 the case A, and means are furnished by which it will always be inserted in the same position in the casing A. The nut c', which engages the stud c, is adapted to fit in an annular recess, c³, at the top of the casing A, and is 80 notched out at either side to correspond with the openings b b', through which the legs of the hasp B are adapted to be inserted.

A notch, c⁴, in the back of the hasp B, is 85 adapted when the hasp is withdrawn and turned to the position as shown in Fig. 2 to come opposite the nut c' and permit the said nut to be turned on the stud c, the said nut being held against revolution on the said stud when the legs of the hasp B are inserted 90 through the openings b b'. Means are thus furnished by which the nut may be readily disengaged from the stud and the said stud removed from the casing A when the lock is open, the said nut being held rigidly in position when the lock is closed.

Journalized loosely on the stud c is a series of tumblers, D D' D''. These tumblers are separated from each other on the said stud by small washers e, each of which is provided with a

small projection or spline, e' , adapted to engage in a longitudinal groove or keyway, e^2 , in the stud e , to prevent the washers from turning on said stud.

5 The leg a' of the hasp B is made of considerable length and adapted to project down through the casing A, past the tumblers D D' D², and is provided on one side thereof with notches $f f' f^2$, in which the respective tumblers are adapted to engage. The other leg, a , of the hasp is made shorter and adapted to project into the casing A far enough to be engaged by the upper tumbler, D, only, a notch, f^3 , being provided therein for this purpose. Each 15 tumbler is provided on one side with a notch, g , which when turned opposite the leg a' of the hasp B will permit said hasp to be withdrawn past the said tumbler. When the notches g in the respective tumblers are brought 20 in line opposite the leg a' of the hasp, the said hasp may be withdrawn, thus opening the lock.

The upper tumbler, D, being adapted to engage with both legs of the hasp, is provided with an additional notch, g' , on the opposite 25 side thereof from the notch g , so that when the notch g is brought opposite to the leg a' the notch g' will stand opposite to the leg a . Each of the disks is provided in the face thereof with a series of holes, g^2 , into one of which a 30 stud, h , is adapted to be inserted. The stud h is preferably screw-threaded and adapted to be inserted into either hole of the series, each of which is correspondingly tapped out to receive the same.

35 The middle tumbler, D', is provided with two studs, one at the top and the other at the bottom thereof, the upper and lower tumblers being provided with only one of said studs at the top and bottom thereof, respectively. 40 These studs are placed at an equal distance from the center of the shaft or stud c , so that as the tumblers are revolved on said shaft the studs h on the respective tumblers will come in contact, and the tumblers will be revolved 45 together.

The lower tumbler, D², is provided with a hub, k , adapted to project downward and rest against the dial-plate A'. This hub k is provided at its lower end with small notches k' 50 therein, one of which is adapted to engage on a projecting stud, l , on the dial-plate A'. It will be seen now that by revolving the dial-plate A' the lower tumbler, D², being connected thereto by the projecting stud l , will be 55 revolved on the shaft or stud c .

When the dial-plate is revolved until the studs h in the respective tumblers come in contact, the notches in the upper disk, D, may be brought opposite to the legs of the hasp by 60 turning the dial-plate to the first number of the combination which corresponds with the said notches. Upon revolving the dial-plate backward or in the opposite direction until the studs engage on the opposite side, the notch 65 in the tumbler D' may be stopped or brought opposite to the notch in the upper tumbler by

turning to the second number of the combination. By again reversing the motion of the dial-plate the notch in the lower tumbler may be brought in line with the others by turning 70 to the third number of the combination. The notches thus all being brought in line, the hasp may be readily withdrawn. Now, as the hasp is withdrawn in order that the tumblers may be held against revolution or accidental displacement, I extend the leg a' of the hasp for some distance below the lower tumbler, (the extended portion of said hasp being preferably of a plain cylindrical shape,) and I provide the said hasp with a stop adapted to limit the 75 movement thereof, so that when the hasp is withdrawn sufficient to open the lock the extended portion of the hasp is brought into the notches of the respective tumblers and the said tumblers thus held against revolution. 80

The stop which limits the movements of the hasp is formed by constructing on the inner side of the casing A a projection, m , on either side of the leg a' of the hasp, thus forming a semicircular chamber for said leg, which also 90 serves as a guide therefor. The projections m are extended downward to a point opposite to or slightly below the tumbler D². On the lower end of the leg a' of the hasp is a small plate, m' , preferably secured thereon by a 95 screw, m^2 , which screws into the end of said hasp. As the hasp is withdrawn the plate m' comes against the projection m , and thus limits the movement of said hasp.

It sometimes happens in locks of this class 100 that in turning the dial-plate until the notch g in the lower tumbler comes opposite the hasp, and pulling on said hasp, the presence of the notch may be detected and the number opposite to said notch noted. By reversing the 105 movement of the dial and repeating the operation the numbers corresponding with the notches in the different tumblers may be similarly detected. To obviate this I so construct the notches in the hasp B that a longitudinal 110 movement of the hasp sufficient to engage in the notch in the lower tumbler is permitted before the hasp comes in contact with the other tumblers of the series. By this construction when the first tumbler is turned with the notch 115 g opposite to the hasp, if the hasp is withdrawn sufficient to come in contact with the next tumbler of the series, the lower tumbler and the dial-plate will be held against revolution, so that the hasp must be forced back into its 120 normal position before the operation of unlocking can be proceeded with. The location of the notch in the first tumbler might be discovered, but this is as far as the operation could proceed.

In order to still further reduce the possibility of opening the lock, I provide on the under side of the lower tumbler a series of false or blind notches, g^3 . These notches are of the same size as the notch g , but extend only half-way 125 through the plate. In case, therefore, the hasp is drawn outward during the revolution of the

dial-plate, the hasp will engage in one of the notches g^3 , which will hold the dial-plate against revolution until the hasp is forced into its normal position. In this way it will be 5 impossible to tell whether the hasp has entered the notch g or into one of the blind notches g^3 . Consequently no number of the combination can be accurately determined.

It will be seen that by the constructions 10 above described I provide a lock which is simple and compact in its construction and very efficient in its operation. By changing the studs h in the different holes of the series 15 of the said tumblers, and by changing the projection l into the different slots k of the lower disk, the combination may be almost infinitely varied.

In assembling the parts of the lock the hasp is inserted into the casing through the openings b b' , and secured therein by means of the plate m' , the lower end of the casing being at 20 this time entirely open. The dial-plate and the respective tumblers and the washers are then placed on the stud c , with the notches in 25 the respective tumblers in line. The stud or shaft c is then inserted into the casing A until the projecting end c^3 passes through the opening c^2 . The hasp is withdrawn and turned to the 30 position as shown in Fig. 2, thus holding the tumblers from turning and at the same time bringing the notch c^3 opposite to the nut c' , to 35 permit said nut to be screwed onto the end of the stud c , thus closing the lower end of the casing A and binding the whole firmly together.

When the hasp is inserted into the casing and the dial-plate revolved, the tumblers are brought to engage in the respective notches, thus locking said hasp firmly in position. The 40 legs of the hasp projecting through the notches in the nut c' also locks said nut, so that when the lock is closed all possibility of opening the same without the combination is precluded.

I have shown in the drawings three tumblers, 45 though it is obvious that any number may be used. It is also evident that the constructions herein shown may be varied in many other different ways without departing from the spirit of my invention.

Having thus described my invention, I 50 claim—

1. The combination, with the outer casing and the dial-plate and the tumblers adapted to be revolved by said dial-plate, of the hasp 55 adapted to be engaged by said tumblers, said hasp being provided with an extended portion adapted when the hasp is withdrawn to be drawn into engagement with and lock the said tumblers when the lock is open, substantially 60 as set forth.

2. The combination, with the outer casing, the dial-plate, and the tumblers adapted to be revolved by said dial-plate, of the hasp provided with notches adapted to be engaged by 65 said tumblers, the notches in said hasp being so arranged in relation to said tumblers that

the hasp is capable of longitudinal movement sufficient to engage with the lower tumblers, and thus lock the dial-plate before coming into contact with the other tumblers of the series, substantially as set forth.

3. The combination, with the outer casing and the dial-plate journaled thereon, and the tumblers adapted to be revolved by said dial-plate, of the hasp provided with notches 75 adapted to be engaged by said tumblers, and the lower tumblers provided with a series of false or blind notches, substantially as and for the purpose set forth.

4. The combination, with the outer casing, 80 the dial-plate journaled thereon, the tumblers adapted to be revolved by said dial-plate, and the hasp provided with notches adapted to be engaged by said tumblers, of a central shaft or stud on which said dial-plate and tumblers 85 are adapted to be revolved, a circular nut at the top of said casing adapted to support said stud, said nut being provided with notches on either side, through which the legs of the hasp extend when the lock is closed, and thus hold 90 the nut against revolution, and the notch in the back of said hasp adapted when the said hasp is withdrawn to come opposite to said nut to permit the same to be revolved to loosen said stud on shaft, substantially as set forth. 95

5. The combination, with the outer casing having the openings in the top to receive the legs of the hasp and provided on one side with projections at the side of said hasp adapted to form a guide therefor, and a stop-plate on said 100 hasp adapted to come against said projections, of the dial-plate and the revolving tumblers adapted to be moved thereby, substantially as set forth.

6. The combination, with the outer casing 105 and the dial-plate journaled thereon, the locking-tumblers adapted to be revolved by said dial-plate, of the hasp B , adapted to be engaged by said tumblers, said hasp being provided with an extended portion adapted to 110 lock said tumblers when the hasp is withdrawn, the stop projection on said casing, and a plate on said hasp adapted to engage therewith, substantially as and for the purpose set forth. 115

7. The combination, with the outer casing and the dial-plate journaled thereon, the tumblers adapted to be revolved by said dial-plate, one of said tumblers being provided with a series of false or blind notches, of a hasp, B , 120 adapted to be engaged by said tumblers, said hasp being provided with notches of varying sizes, so that a movement thereof sufficient to engage with the blind notches is permitted without bringing said hasp in contact with 125 the other tumblers of the series, substantially as set forth.

8. The combination, with the outer casing, the dial-plate thereon, the revolving tumblers adapted to be moved by said dial-plate, the 130 central stud for supporting said tumblers and dial-plates, of a hasp provided with notches

adapted to be engaged by said tumblers, said hasp being extended and provided with a stop-plate adapted to engage with a stop projec-
5 tion on said casing, so that the extended por-
tion will be brought into engagement with
and lock the tumblers when the hasp is with-
drawn, and a nut for supporting said stud,
said nut being held from turning while the

lock is closed and adapted to be released when
the lock is open, substantially as set forth.

In testimony whereof I have hereunto set my
hand this 15th day of April, A. D. 1886.

JOHN H. JULIAN.
